SEWING MACHINE BELT GUARD OR SIMILAR ARTICLE

Melvin R. Chase, 37 Westford St.,
Saugus, Mass. 01906

Filed Nov. 2, 1973, Ser. No. 412,209

Term of patent 14 years

Int. Cl. D15—06

U.S. Cl. D70—2 A

FIG. 1

FIG. 2

FIG.4

FIG. 1 is a front elevational view of a sewing machine belt guard showing my new design;

FIG. 2 is a rear elevational view thereof;

FIG. 3 is a side elevational view thereof;

FIG. 4 is a side elevational view thereof from the opposite side;

FIG. 5 is a bottom plan view; and

FIG. 6 is a top plan view.

I claim:

The ornamental design for a sewing machine belt guard of similar article, substantially as shown.
